STOCKING

Clarence Nye, Reading, Pa.

Application February 20, 1953, Serial No. 23,703

Term of patent 14 years

(Cl. D47—7)

To all whom it may concern:

Be it known that I, Clarence Nye, a citizen of the United States of America, residing at Reading, in the county of Berks and State of Pennsylvania, have invented a new, original, and ornamental Design for a Stocking of which the following is a specification, reference being had to the accompanying drawing forming part thereof.

Fig. 1 is a rear perspective view of a stocking embodying my novel design.

Fig. 2 is a fragmentary rear elevational view of the stocking shown in Fig. 1.

I claim:

The ornamental design for a stocking, substantially as shown.

CLARENCE NYE.
